UNITED STATES PATENT OFFICE.

CHARLES H. FOSTER, OF ELIZABETH, NEW JERSEY, ASSIGNOR TO THE SINGER MANUFACTURING COMPANY, OF NEW JERSEY.

SEWING-MACHINE TRIMMER.

SPECIFICATION forming part of Letters Patent No. 630,209, dated August 1, 1899.

Application filed January 12, 1898. Serial No. 666,440. (No model.)

To all whom it may concern:

Be it known that I, CHARLES H. FOSTER, a citizen of the United States, residing at Elizabeth, in the county of Union and State of New Jersey, have invented certain new and useful Improvements in Sewing-Machine Trimmers, of which the following is a specification, reference being had therein to the accompanying drawings.

10 This invention has for its object to provide an improved sewing-machine trimming device by means of which the projecting edge of the lower layer of two superposed pieces of material may be trimmed off parallel with 15 the seam close to the edge of the upper layer and simultaneously with the sewing operation, the trimming-knife being so arranged and operated that it will make undercutting strokes, so that the under side of the lower 20 layer or piece of material of the finished work will be slightly within the edge of the upper layer thereof. The improved trimming device is more particularly intended for use in shoework, as in trimming off the projecting 25 edges of the linings of the lacing-flies or shoe-tops, in which the outer or upper layers have their edges turned in next to the linings and pasted down, forming finished edges, beyond which the edges of the linings project as the 30 parts are superposed for sewing, so that the edges of the trimmed-off linings are somewhat raw or unfinished. It is desirable that these raw or unfinished edges in the work should be slightly within or under the turned- 35 in finished edges, so as to be concealed by the latter, and this desideratum is effected in the present invention by an undercutting trimming-knife.

In carrying the invention into effect the 40 reciprocating trimming blade or knife is arranged and reciprocated in an inclined position relative to a vertical plane and sidewise relative to the seam, said knife being preferably provided with a bent steadyng or guid- 45 ing finger extending below the cutting edge of the knife and entering a hole in the throat-plate. The knife, which is preferably a thin elastic steel blade, is preferably attached to a pivoted or tilting block carried by a stock 50 or small bracket secured to the lower end of the trimmer-bar in such a manner that the

cutting edge of the knife will be caused to describe a curved path as it travels up and down, so that the lower face of the layer of material being trimmed will be cut farther 55 in under the finished edge of the upper layer than would be possible if the cutting edge of the knife reciprocated in a right-line path inclined relative to the path of the needle. Instead, however, of attaching the knife to a 60 tilting or rocking block the cutting edge of the knife may be caused to travel in a curved path simply by the engagement of the projecting bent finger on the knife with the throat-plate, the thin steel knife-blade having 65 sufficient elasticity so that it will spring enough to effect this result. The work is guided to the needle and trimming-knife by a guide or gage, against the guiding-face of which the finished edge of the upper layer of 70 material is held by the attendant, so that the line of stitching and line of trimming will always have a certain relation to the said finished edge of the upper layer of material.

In the drawings, Figure 1 is a front end elevation of the upper part of a sewing-machine with the improved trimmer applied thereto, the face-plate being removed; and Fig. 2 is a sectional side view of the same. Fig. 3 is a plan view of the throat-plate and one form of 80 guide, and Fig. 4 a sectional view of the latter on line *y y* of Fig. 3. Fig. 5 is a cross-section of the throat-plate on line *x x* of Fig. 3. Fig. 6 is a detail side view of the knife and its carrier. Fig. 7 is a broken-out plan view 85 of the form of guide preferably employed. Fig. 8 is a detail view illustrating a slight modification, and Fig. 9 is a detail sectional view illustrative of the work.

A denotes the head or front end portion of 90 the bracket-arm of a sewing-machine, B the driving-shaft, and C the needle-bar, connected to a crank at the front end of said shaft by a pitman *c*.

D is the trimmer-bar, connected by a spring- 95 pressed pin *d* to an arm *d'* of a short rock-shaft *d''*, having a second arm *d'''*, forked to embrace an operating-eccentric *b* on the shaft B, this trimmer-bar-operating mechanism being of well-known construction.

E is the knife-carrier, secured to the lower 100 end of the trimmer-bar D, and *e* is the knife,

which is preferably connected with said carrier by a block e^2 , pivotally attached to said carrier by a pin e^3 . The knife e is preferably provided with a bent depending finger e^4 , which enters a hole f in the throat-plate f' , the said knife being attached to the pivoted block e^2 by screws e^5 and a clamping-plate e^6 . The rear face of the carrier E , with which the block e^2 is in contact, is of different form from the contiguous face of said block, so that the latter may have a limited rocking movement on the said face, a spring e^7 normally holding said block in the position shown in Figs. 2 and 6, but said spring yielding under pressure to permit the block to rock.

The right or rear face of the bent finger e^4 on the knife normally presses against the top of the right or rear wall of the slot f in the throat-plate, (the front or left wall of said slot being inclined or beveled, as shown in Fig. 5,) so that as the knife descends the pressure of said finger against the throat-plate will rock the block e^2 slightly on its pivot-pin, compressing the spring e^7 , and thus cause the cutting edge of the knife to describe a curved path as it descends and which if continued far enough down would intersect the plane of the path of the needle, thus giving a more pronounced undercut than would result if the edge of the knife traveled simply in a right line inclined path. This right or rear wall of the slot f is preferably formed by a spring-pressed or yielding plate f^2 , which will insure a proper cutting action, but which will yield under sufficient pressure, and thus avoid breakage. The inclined elastic knife-blade, with its bent finger, would spring enough to effect this result were it directly attached to the carrier E , as shown in Fig. 8; but it is better to connect the knife with the carrier through the pivoted block, as there is less friction and less danger of breaking the knife.

The work-guide is formed at the forward end of a shank G , which is preferably attached to an adjustable plate g , but which may be integral with said plate, said guide comprising the overhanging lip g' , which is to rest on the top of the layer of fabric, and the vertical guiding face or wall g^2 , against which the edge of the said upper layer will rest to properly guide the work to the needle and trimming-knife. Said guide also preferably comprises the slender finger g^3 , close to the outer or right face of which the needle descends and close to the inner face of which the cutting edge of the knife descends. The plate g is adjustably secured by a screw g^7 to a base-plate g^4 , which is fixed to the work-plate of the machine, as by screws g^8 , the lateral position of the plate g and of the guide connected therewith determining the distance of the stitches from the edge of the work. The guide is supported above the throat-plate f' far enough to permit the edge of the lower layer of material which is to be trimmed off

to pass beneath it, said guide being vertically adjustable to accommodate different thicknesses of material of either or both layers by means of the screw h^2 impinging against the plate g^4 , the plate g springing enough to permit of this adjustment.

To throw the trimmer-bar out of action, it is only necessary to withdraw the spring-pressed locking-pin d from its engaging notch d^4 in the trimmer-bar D , when the spring d^5 will lift the said bar so that the knife will be out of the way of the work. At such times it is frequently desirable that the work-guide should also be removed, so that the attendant can direct the work to the needle independently of said guide. To this end the guide-carrying plate g is preferably connected with the base-plate g^4 by a spring-pressed locking-slide g^5 , so that when said locking-slide is withdrawn from its engaging notch in said plate g the latter will be thrown to the right out of the way by a retracting-spring g^6 provided for this purpose.

As I believe that I am the first to construct a sewing-machine trimming device in which a reciprocating trimming-knife is inclined relative to a vertical plane and sidewise to the seam or to the direction of the feed of the work and is reciprocated in the direction of its length in this position, so as to be adapted to trim off with undercutting strokes the projecting edge of the lower layer of two superposed pieces of material simultaneously with the sewing operation and so as to leave the cut edge of the lower layer h of the work slightly within the uncut edge h' of the upper layer of the work, I do not wish to be understood as limiting my invention to the details herein shown and described, as these may be varied widely without departing from the essence of the invention.

Having thus described my invention, I claim and desire to secure by Letters Patent—

1. In a sewing-machine, the combination with a vertically-reciprocating trimmer-bar, of a pivoted block connected therewith, a knife attached to said block and which is inclined relative to a vertical plane, and means for causing said block to rock or tilt as the said bar is reciprocated, thereby giving an undercutting action to the edge of the said inclined knife, and a coöperating throat-plate.

2. In a sewing-machine, the combination with a trimming-knife which is inclined relative to a vertical plane and sidewise of the seam, a throat-plate coöperating with said knife, and means for reciprocating said knife in the direction of its length to undercut the lower of two superposed pieces of material, of a guide supported above the work-plate so as to guide the edge of the upper layer of two superposed pieces of material, while permitting the projecting edge of the lower layer to pass beneath it, said guide having a vertical guiding-wall and, at its extreme end, an over-

hanging lip *g*' above said wall, and means for adjusting said guide vertically to accommodate materials of different thicknesses.

3. In a sewing-machine, the combination with an inclined, reciprocating trimming-knife having a depending bent finger projecting below the cutting edge of said knife, of a throat-plate having a hole or slot for receiving said finger and which latter, by its contact with the wall or walls of said slot, will cause said cutting edge to travel in a curved path.
4. In a sewing-machine, the combination

with a throat-plate and a reciprocating trimming-knife which is inclined relative to a vertical plane and sidewise to the seam, of means for reciprocating said knife in the direction of its length, and guiding means for causing the cutting edge of said knife to travel in a curved path as it is reciprocated.

In testimony whereof I affix my signature in presence of two witnesses.

CHARLES H. FOSTER.
